DISTILLATION OF TAR, ETC.

Stuart Parmele Miller, Englewood, N. J., assignor to The Barrett Company, New York, N. Y., a corporation of New Jersey

Application August 30, 1929. Serial No. 389,345

14 Claims. (Cl. 202—30)

This invention relates to the recovery of by-products from hot coke oven gases according to which the gases from a battery of coke ovens are fractionally cooled to produce a heavier tar 5 and a lighter tar and the lighter tar is distilled to produce clean distillate. The distillation of the lighter tar may be carried on in various ways and various products may be produced. The invention relates more particularly 10 to the recovery of a heavier tar fraction which is suitable for use in road construction without distillation and also a lighter tar or tarry oil fraction which on distillation and extraction gives a high yield of tar acids. The invention 15 includes both the process and apparatus for carrying it out.

According to the ordinary method of operating a coke oven plant, the hot coke oven gases from the various ovens are collected in a gas 20 collector main and subjected to partial cooling during which a heavy tar is separated from the gases and the resulting partially cooled gases are passed to a condensing system where lighter tar or tarry oils are separated from the gases. 25 The heavy tar from the collector main and tarry oil from the condensers are ordinarily blended and shipped to a tar distillation plant for the production of distillate oils and pitch. Although the heavier tar from the collector main 30 and the lighter tar or tarry oil from the condensers comprise the chief tar products, other tars may be formed, as, for example, a tar which separates from the gases in the cross-over main. This tar is ordinarily blended with 35 the tarry oil obtained from the condensers and the mixed tar thus produced is blended with the heavy tar from the collector main to produce a total tar.

According to the present invention, the hot 40 coke oven gases are fractionally cooled but the various tar fractions produced are collected separately and a lighter fraction is subjected to distillation to produce distillate oil and pitch. The cooling is preferably regulated to yield a 45 heavier tar which may be used directly as a road tar or which may be blended with other tars to produce road tars of desired characteristics. For example, the heavier tar produced according to this invention may be blended with gas 50 house tar of relatively high free carbon content when a high free carbon road tar is desired, or with water gas tar of relatively low viscosity when a comparatively fluid road dressing is desired.

55 The initial cooling of the gases will ordi-

narily occur in the collector main. The gases may be cooled by spraying with a cooling medium, for example ammonia liquor. The amount of spray used and the temperature of the spray are regulated to determine the extent 60 to which the gases are cooled in the gas collector main and thus to control the amount of oils thrown down in the main and the melting point of the tar produced.

Instead of spraying the gases, the gases may 65 be cooled by direct contact with a stream of a cooling medium which is caused to flow through the bottom of the collector main. This stream may be a mixture of ammonia liquor and tar or a stream of tar only may be used. There may 70 be some distillation of the tar used for cooling the gases and the vapors thus produced will pass from the collector main with vapors already present in the gases and on cooling composite oils will separate in the condenser. 75

The cooling of the gases in the collector main may be accomplished by spraying the gases and simultaneously passing a stream of a cooling medium through the bottom of the collector main. The cooling may merely raise the temperature of the cooling medium, or volatilization of a part of the cooling medium may result. For example, water may be distilled where ammonia liquor either alone or together with tar, is used for cooling the gases, or lower boiling 85 constituents of the tar may be distilled where tar is employed as a cooling medium.

After the gases leave the collector main they are further cooled and this cooling may be a fractional cooling to produce different tar fractions or a single tar may be produced by a single stage cooling of the gases. The cooling may be in one or more indirect condensers or direct cooling may be employed by bringing the gases into 90 direct contact with water or ammonia liquor. 95 Where desirable, refluxing or other means for obtaining sharp fractions of tar or tarry oil may be employed.

The cooling in the collector main, regardless 100 of how the cooling is effected, is so regulated that the gases leave the collector main at a higher temperature than ordinarily and the tar obtained from the collector main comprises constituents of higher boiling range and is comparatively free from the lower boiling constituents usually present in such a tar. According to 105 the preferred method of operation, the cooling is so regulated that the tar produced may be used directly as a road tar or may be blended with other tars as above described to give road 110

tars of desired characteristics. The melting point of the tar obtained from the collector main may advantageously be in the neighborhood of 90 or 95° to 110 or 115° F. A method of preparing such products as applied to coal distillation gases enriched in oil constituents is described in my copending application Serial No. 206,368, filed July 13, 1927, which has matured into Patent No. 1,826,431.

10 As obtained from the collector main the tar may be contaminated with ammonia liquor, as, for example, in a main in which the gases are cooled by spraying with water or ammonia liquor. The water or ammonia liquor and tar are advantageously separated before the use of the tar as a road tar although the finished road tar product may contain a small amount of moisture. The tar produced in the collector main according to this method of operating and 20 water gas tar or gas house tar are readily miscible, and they may be blended by directing a stream of each of the tars into a storage tank and so directing the streams of the tars that they unite before hitting the surface of the 25 blended material contained in the storage tank. Agitating means may be provided within the tank, where desirable. The tars may be blended at a somewhat elevated temperature and where this may readily be done, it is beneficial.

30 Where a stream of tar is to be fed into the bottom of the collector main as a part of the collector main operation, the gas house tar or water gas tar or other tar employed for blending with the tar from the collector main to produce a road tar may be delivered directly to the collector main. On passing through the main this tar will serve to cool the gases, at least to some extent, and lower boiling point constituents may be volatilized from this tar although any 40 considerable distillation of the tar in the collector main is not contemplated. By feeding water gas tar or gas house tar to the collector main in regulated amount, a blended pitch suitable for road purposes may be drawn off direct 45 from the collector main and be used directly without distillation or further blending.

According to this invention the lighter tar or tarry oil separated from the gases subsequent to the initial partial cooling is distilled. The 50 condensers may be either direct or indirect condensers and the gases may be cooled to in the neighborhood of 30 or 40° C. before leaving the condensers. The cooling may be regulated to produce desired tar fractions.

55 This separate distillation of the tarry oil from the condensers may be carried out alone, or where all of the heavy tar from the collector main is not employed in road construction, a portion of this heavy tar may be blended with the tarry oil before distillation, or the heavy tar 60 may be separately distilled.

According to the preferred form of carrying out this invention, the gases leave the collector main at a higher temperature than usual and 65 therefore the tarry oil obtained contains a higher percent of oils of higher boiling range than ordinarily. On distilling the tarry oil a high melting point pitch, e. g., a pitch with a melting point of up to 350° F. or 400° F. or 70 higher may be produced. An oil yield as high as 80 or 90% may be obtained, with a correspondingly low yield of high melting point pitch.

75 The distillate is a distillate comprising oils of higher boiling range and may advantageously be blended directly with some undistilled tarry

oil to produce a composition suitable for creosoting purposes. By regulating the amount of tarry oil added to the distillate, the free carbon content of the blended product may be controlled.

80 The distillate may be collected as a single product and used for clean creosote oil, although such an oil will ordinarily be lighter and contain a larger percent of oils of lower boiling range than an oil obtained by the ordinary distillation of a total tar; by carrying the distillation to a pitch of high melting point, however, a creosote oil comprising oils of higher boiling range may be obtained.

85 Instead of cooling the vapors in a single stage, 90 two or more fractions of clean oils may be obtained. Where a heavier oil fraction and a lighter oil fraction are obtained, the lighter oil, containing a relatively high percentage of tar acids, may be extracted for the recovery of the tar acids and with or without the working up of this lighter fraction for naphthalene, the neutral oil remaining after the extraction of the tar acids may be blended back with the heavier fraction for use as creosote oil. Instead of 95 fractionally cooling the vapors resulting from the distillation, the tarry oils may be fractionally distilled by first removing the lighter oils and then, on further distilling, removing heavier oils.

100 Various types of stills may be employed for carrying out the distillation. Where the lighter tar or tarry oils are distilled by bringing them in direct contact with hot coal distillation gases, the last-mentioned process of fractionally distilling the tarry oils by first removing the lighter 105 boiling oils without direct contact of the tarry oils with the hot gases, and then bringing the partly distilled tarry oils into direct contact with the gases is advantageous in order to obviate 110 the necessity of removing vapors of the lighter oils from the large volume of gases which would necessarily be employed in the distillation.

115 The tarry oils are rich in tar acids and naphthalene as compared with total tar and the 120 distillate from such tarry oils will give a high yield of naphthalene and tar acids. The heavy tar from the collector main is correspondingly low in tar acids and naphthalene. This tar is 125 relatively rich in free carbon and also in heavier oils and lower in the lightest oils. These properties are desirable in a road tar.

130 The invention will be further described in connection with the accompanying drawings, but it is intended and is to be understood that it is not limited thereto.

Fig. 1 is a plan view of a coke oven plant equipped for carrying out the invention;

Fig. 2 is an elevation partly in cross-section of the apparatus shown in Fig. 1; and

Fig. 3 is a flow sheet representing various products which may be produced according to the invention.

135 In the drawings 5 is a coke oven battery, the ovens of which are connected through the uptake pipes and goose-necks 6 with the collector main 7. The gases are cooled in the collector main as by spraying with ammonia liquor through the sprays 8 and 9 in the goose-necks and the collector main. The gases pass from 140 the collector main through the center-box 10 to the cross-over main 11 and thence to the condensers 12, 13. The tar from the collector main is drawn off through the center-box to a 145 decanter 14 from which the tar is collected in 150

the tank 15. The cooling in the collector main is regulated by the proper adjustment of the amount of cooling medium admitted through the sprays in the goose-necks and the collector main, the insulation or non-insulation of the collector main, etc. According to this invention the collector main operation is so controlled that the heavy tar produced in the collector main and drawn off into the tank 15 may be used for a road tar without distillation to remove lower boiling constituents.

Where the road tar is to be blended with gas house tar or water-gas tar or some other tar to produce a blended road tar of desired characteristics, this other tar may be mixed with the ammonia liquor sprayed through the sprays 8 and 9, or the tar may be delivered with or without ammonia liquor to the ends of the collector main and flushed through the bottom of the collector main or at one end of the collector main and withdrawn from the other end. In such a case a blended product of higher free carbon content, suitable for use in road construction may be obtained directly from the collector main.

The gases leaving the collector main are cooled in the condensers 12, 13 and this cooling may be by the ammonia liquor sprays 16 or other means such as indirect cooling means may be employed. Where the gases are sprayed with ammonia liquor or are cooled below the dew-point of the gases for ammonia liquor, the tarry oil drawn off from the condensers will be contaminated with ammonia liquor and it will then be drawn off through a decanter such as the decanter 17 and the tarry oils will be separated from the ammonia liquor in the decanter and will be separately collected as in 18. Several tarry oil fractions may be recovered by fractional cooling of the gases and these tarry oil fractions may be separately distilled. According to the invention, at least one of the tarry oil fractions is distilled.

An exhauster is shown at 19 for drawing the gases through the system, and means for the recovery of ammonia and light oils is located beyond the exhauster.

The tarry oils from the condensing system may be distilled in a pipe coil still or any other suitable type of still. The drawings provide means for distilling the tar by the heat of the gases from selected ovens of the battery. The selected ovens are provided with uptake pipes and goose-necks 25 located at the back of these ovens and connecting with the hot gas header 26. By the proper manipulation of valves in the uptake pipes and goose-necks 25 and the uptake pipes and goose-necks 6, the gases from these selected ovens may be directed either to the collector main 7 or through the header 26 into the still 27.

Within the still is a roll 28 which is located at one side of the still and driven by the motor 29 at a speed of 900-1200 R. P. M. The tar is distilled within the still and the pitch produced is withdrawn through the trap 30 and the levelling arm 31. The level of tar within the still is regulated by the position of the levelling arm 31. Where a high melting point pitch is produced, for example a pitch with a melting point in the neighborhood of 400° or higher, the pitch as it comes from the still is advantageously sprayed with water from the line 32 in the trough 33 so that it is chilled and granulated

and is delivered to the storage bin 34 in the form of hard granules.

The hot gases passing from the ovens through the header 26 and the still 27 pass up through the tower 28 and thence to the condenser or heat interchanger 29. The gases are partially cooled in the heat interchanger and then pass to the condenser 53, and thence to an exhauster and means for the recovery of ammonia and light oils, which may be the exhauster 19, and the same means for the recovery of ammonia and light oils as that employed for treating the gases collected in the collector main 7 and passed through the cross-over main 11 and the condensers 12, 13.

The tarry oil which is to be distilled may be fed directly to the still or it may be fed through a nozzle, such as the nozzle 35, in the tower 28. Baffles 36 and 37 below and above the nozzle tend to bring the tar sprayed in through the nozzle 35 into intimate and prolonged contact with the hot gases and to remove entrained particles of spray from the gases. The tar which is partly distilled by the hot gases in the tower collects in the bottom of the tower and is advantageously passed through the line 38 to the end of the still at which the hot gases enter the still. The gases and tar thus pass through the still in a concurrent direction and the tar is distilled to pitch. By properly regulating the speed of the rotation of the roll and the depth to which it dips into the tar, an intense spray of tar may be produced within the gases in the still so that the gases are detarred. The gases leaving the still are then substantially clean gases and on cooling clean oils will be obtained.

According to a preferred method of carrying out this invention, the tarry oil from the tank 18 is pumped by the pump 40 through the line 41 and in the condenser or heat interchanger 29 this tarry oil is brought into indirect contact with the hot gases and vapors leaving the still. In this heat interchanger the tar is heated and partially distilled. From the heat interchanger the tar is brought into the vapor chamber 42 in which the vapors produced are separated from the undistilled tar residue. The vapors pass through the main 43 to the condenser 44. This may be a condenser of the direct or indirect type in which the vapors of lower boiling range 125 distilled from the tar in the heat interchanger 29 and separated in the vapor box 42 are condensed. The clean oils produced are drawn off into the receiver 45.

The distillation residue from the vapor chamber 42 is pumped to the spray nozzle 35 in the tower 28 thru the line 46 by the pump 47. This partly distilled tar is further distilled by contacting with the gases and vapors in the tower 28 and is heated and then passes into the still 135 where it is further distilled. According to a preferred method of operating, a high melting point pitch, for example, a pitch with a melting point of 400° F. is produced, and drawn off into the pitch receiver 34.

The lower boiling constituents of the tarry oil are separated in the vapor chamber and are readily condensed in the condenser 44. The residue of the tarry oil which is free from lower boiling constituents is distilled within the still 135 27, and the gases and vapors of higher boiling constituents pass from the still thru the main 50 into the condenser 29 where higher boiling clean oils are condensed by indirect contact with the tarry oil. The heavy clean oil which sepa-

rates in this condenser 29 is withdrawn into the receiver 51. The partially cooled gases and vapors pass from the condenser 29 thru the main 52 to the condenser 53 where further clean

scribed in "Methods of analysis used in the coal tar industry" by J. M. Weiss in the Journal of Industrial and Engineering Chemistry, vol. 10, No. 10, October, 1918, page 817.

5 oils are separated and drawn off into the receiver

I claim:

54. Owing to the fact that the lower boiling constituents of the tarry oils are removed before the tarry oils are brought into direct contact with the gases, the cooling in the condensers 29 and 53 need only be such as to remove higher boiling oils. The loss of low boiling constituents in the gases is low and the yield of oils is therefore high. A yield of 80-85 or 90% of oil may be obtained.

85
1. The method of recovering by-products from

15. In the operation of a coke oven battery in order to produce a tar suited for use as a road tar, 60-65% of the tar may be separated in the collector main. The remaining 40-35% will be collected from the condensers as tarry oil. This 20 tarry oil product may be distilled to produce 80-85% oil, and 20-15% of a high melting point pitch will be obtained. The oil yield may therefore be, for example, 29.75-32% of the total tar and the pitch will be the balance or 5.25-8%.

90
2. The method of treating hot coke oven gases, which comprises collecting the gases in a collector main while still hot, subjecting them to regulated cooling in the collector main, cooling the gases leaving the collector main to separate

25. The yield of products obtained will depend upon the length of the coking cycle in the ovens, the temperatures employed, etc. The above example is merely illustrative. A further discussion of possible products, which is also 30 merely illustrative, is given below in connection with Fig. 3. The percentages of the various products employed and the percentage yields are not shown in Fig. 3 since these figures are dependent upon many variables and will vary 35 from battery to battery.

95
3. The method of treating hot coke oven gases, which comprises collecting the gases in a collector main while still hot, subjecting the gases to regulated cooling in the collector main, further

35. The gases from the battery *a* are partially cooled to produce a heavy tar *b* and tarry oil *c*. The tarry oil is distilled to produce pitch *d* and one or more clean oil distillates are obtained as, 40 for example, the heavier oil fraction *e* and the lighter oil fraction *f*. The lighter oil fraction may be extracted for tar acids *g* and then chilled for the recovery of naphthalene *h*. The neutral oil *i* which remains may be blended with 45 the heavier oil *e* and with tarry oil *c* or heavier tar *b* to produce creosoting composition *j*. The products from the tarry oil distillation, according to a preferred method of operation, are therefore the pitch *d*, naphthalene *h*, tar acids 50 *g* and creosoting composition *j*. The heavy tar *b* is blended with gas-house tar *k* to give road tar *l*.

100
4. The method of treating hot coke oven gases, which comprises collecting in a collector main

55. As an alternative arrangement, the neutral oil *i* may be used for Diesel oil. It may be blended with heavier oil *e* to produce a clean creosote oil. It may be used to cut back tar or pitch and the blended mixture burned for fuel.

105
5. The method of treating hot coke oven gases,

60. Instead of blending the heavier tar and tarry oil produced from the operation of a coke oven battery, the heavy tar and tarry oil are separately collected, according to this invention, and the tarry oil is distilled and one or more marketable products may be produced. According to the preferred method of operation, the 65 operation of the collector main is so adjusted that the tar produced in the collector main is suitable for use directly as road tar or is suitable for blending with a tar of higher free carbon content, such as gas-house tar, or with 70 a tar such as water-gas tar to produce road tar having desired characteristics. In this manner the tar from the collector main may be used for road treating purposes without being distilled.

- which comprises collecting the gases from the ovens in a collector main at substantially the temperature at which they leave the ovens subjecting the gases to regulated cooling in the 5 collector main to produce a road tar, cooling the gases leaving the collector main to separate tarry oil therefrom, passing the gases from selected ovens of the battery through a still, bringing the gases and vapors from the still into indirect heat interchange relation with the tarry oil, whereby the tarry oil is heated above the boiling point of its lower boiling constituents, passing the heated tarry oil to a vapor box, separating vapors of lower boiling constituents from the undistilled residue, cooling these vapors to obtain a clean oil of low boiling range, distilling the undistilled residue by bringing it into direct contact with the hot gases in the still whereby the undistilled residue is distilled and 10 the gases and vapors resulting from the distillation are employed for heating the tarry oil by being brought into indirect heat interchange relation therewith. 7. In connection with a coke oven battery a gas collector main, a separate receiver for the heavy tar produced in the collector main, a condenser for cooling the gases leaving the collector main, a separate tarry oil receiver for the condensate from the condenser, a still, means for passing gases from a plurality of ovens through the still, a second still comprising a heat interchanger for cooling the gases and vapors leaving the first still and for heating the tarry oil thereby, means for separately 25 conveying the tarry oil through the second still in indirect heat interchange relation with the gases and vapors passing therethrough, a cooler for condensing vapors distilled from the tarry oil in the second still, and means for conveying the distillation residue of the tarry oil to the first still. 8. In connection with a coke oven battery, a gas collector main, a separate receiver for the heavy tar produced in the collector main, a condenser for cooling the gases leaving the collector main, a separate tarry oil receiver for the condensate from the condenser, a still, means for passing gases from a plurality of ovens through the still, a heat interchanger for 30 cooling the gases and vapors leaving the still, means for conveying the tarry oil through the heat interchanger in indirect heat interchange relation with the gases and vapors passing therethrough, a vapor chamber, means for con-
- veying the heated tarry oil from the heat interchanger to the vapor chamber, a condenser for cooling the gases leaving the vapor chamber, and means for conveying residue from the vapor chamber to the still. 9. The method of producing road tar which comprises bringing gas house tar into direct contact with coke oven gases as they are cooled in the collector main of a coke oven battery and regulating the cooling and amount of gas house tar blended with tar from the gases so as to produce a blended tar product with a melting point between 90 and 110° F. 10. The method of producing road tar which comprises bringing gas house tar into contact with hot coke oven gases resulting from the destructive distillation of coal in coke ovens as the gases are cooled in the collector main of a coke oven battery and regulating the cooling and the amount of gas house tar blended with tar from the gases so as to produce a blended tar product with a melting point between 90 and 115° F. 11. The method of treating coke oven gases which comprises collecting them in a gas collector main and then cooling them in coolers and separating from the gases between the time they leave the oven and the time they enter coolers, tarry constituents which together have a melting point between 90 and 115° F. 12. The method of treating coke oven gases resulting from the destructive distillation of coal in coke ovens which comprises fractionally cooling them so as to separate from the gases as one fraction tarry constituents with a melting point between 90 and 115° F. 13. The method of treating coke oven gases which comprises cooling coal distillation gases resulting from the destructive distillation of coal in coke ovens which comprises collecting the gases from a plurality of coke ovens and collecting them and cooling them before and during the collecting so as to separate from the gases tarry constituents with a melting point between 90 and 115° F. 14. The method of treating distillation gases which comprises collecting the gases resulting from the destructive distillation of coal in a plurality of coke ovens and passing them to a cooler and cooling the gases before they enter the cooler so as to separate from them tarry constituents with a melting point between 90 and 115° F.
